LINT SCREEN

Michael P. Gosnell, Philadelphia, Pa., assignor, by mesne assignments, to Philco Corporation, Philadelphia, Pa., a corporation of Delaware

Filed May 26, 1961, Ser. No. 113,025

4 Claims. (Cl. 68—20)

This application relates to lint screens for combination washing and drying machines.

It is usual to dry fabrics in such a machine by circulating hot air, a process in which lint is dislodged from the fabrics and entrained by the circulating air. Lint screens have been used to filter the entrained lint from the air.

The lint screens heretofore made and used have generally been workable, but have caused problems, for lint constituents tended gradually to accumulate on such a screen, filling and clogging the screen apertures and thus interfering with proper performance of the machine. Thus far it has not been possible to remove the collected material completely, except by arrangements which were cumbersome, unduly expensive, unreliable, or in need of more attendance and service than is available, especially in a home laundry.

It is an object of my invention to provide a machine of the indicated type with improved, simple and economical lint screen apparatus, complete with cleaning means adapted substantially to prevent undesirable accumulations of lint deposits.

For this purpose the invention provides a perforated or foraminous, normally stationary disc, means for controllably moving said disc in axial directions, and means for rotating it upon axial motion in one of said directions. The disc is first axially moved into a stationary and lint screening position, which is maintained during a fabric drying operation in the washer-dryer. Thereafter and during a washing operation applied to a new load of fabrics, the screen disc is axially moved into a cleaning position wherein it is rotated in washing water, preferably by power derived from the rotating fabrics drum of the machine. The rotation serves to clean the disc by removing previously intercepted lint from the screen, thus preparing the screen for a new and effective lint screening operation, and the required cleaning of the screen is greatly promoted and improved by certain added features, all of which will best be explained in the following description of a machine incorporating the invention.

FIGURE 1 is a general rear view of said machine. FIGURE 2 is an elevation; it is drawn on a slightly larger scale and partly in sectional view taken approximately along line 2—2 in FIGURE 1. FIGURE 3 is a detail side view drawn on a still larger scale and showing the lint screen apparatus in generally vertical sectional view. FIGURE 4 is a view generally similar to that of FIGURE 3 but showing a modified construction.

Tub 10 of the illustrated washer-dryer (FIGURES 1 and 2) has the usual pair of closure plates 11, 12, disposed in rear portion 13 of a cabinet 14, and in specific accordance with the invention, as best shown in FIGURE 3, the space between these plates is divided into a small lower drain chamber 15 and a larger surrounding and overlying air circulation chamber 16. For this purpose a cylindrical wall or partition 17 extends between said plates 11

2

and 12 and is secured to suitably apertured portions of said plates by flanges 18. The new lint screen 19 is a perforated disc, disposed in the rear portion of tub 10 and overlying the front end of drain chamber 15 or in other words overlying the open portion of the inner closure plate 12. The disc is shown as being of conical shape with an apex pointing away from the rear of closure plates 11, 12 and into tub 10.

As already indicated, the screen disc 19 can be reciprocated horizontally along its axis. In the illustrated form of the invention the disc, disposed in the rear portion of tub 10, is normally biased into the tub, that is, toward the right as seen in FIGURES 2 and 3, by a spring 20, while being adapted to be forced to the left, in other words against plate 12, by a solenoid 21. For these purposes one end of spring 20 is held by a bracket 22 rigidly mounted on the rear surface of the outer closure plate 11 while the other end of said spring abuts against a shouldered washer 23 and thereby against an abutment and holder member 24 in drain chamber 15, which member in turn has a central portion abutting against the rear end of a horizontal shaft 25. The front end portion of this shaft has lint screen 19 secured thereto and also has a roller wheel 26 secured thereto in front of the lint screen, this wheel being adapted in one position of the shaft to be engaged and rotated by a circular flange or lip 27 on the vertical rear surface of the fabrics drum 28 in tub 10. The drum is suitably supported in a bearing unit 29 installed between the rear closure plates 11, 12; the drum is driven by a pulley 30 in the rear portion 13 of the cabinet.

The lint screen shaft 25 is slidably and rotatably held in a bearing 31, secured to outer closure plate 11 by a structural support 32 which extends into chamber 15. The rear opening of chamber 15 through which the bearing support 32 is inserted into this chamber is closed by a liquid-tight flexible sheet 33, having a peripheral portion secured to plate 11 and a central portion held by and between the washer and abutment members 23, 24.

In order to provide for leftward axial motion of lint screen 19 and drive wheel 26, against the force of spring 20, the screen actuating shaft 25 has a washer 34, secured to a shouldered rear end of the shaft by a pin 35, while abutment and holder member 24 has jaws 36 adapted to engage the front surface of this washer and to move the washer, the shaft, the screen, and the drive wheel toward the left, urged by a cable 37. This cable interconnects solenoid 21 with a fitting 38 on the rear end of washer 23. The cable is shown as being disposed in a flexible casing 39, one end of which is secured to the aforementioned bracket 22 while the other end is secured to a bracket 40 on solenoid 21.

In operation the fabrics to be washed and dried are introduced into drum 28 through a front door 41 of cabinet 14 (FIGURE 2). By means of suitable controls (not shown) a motor 42 is then started (FIGURE 1) to rotate pulley 30 and thereby drum 28 (FIGURE 2). By means of suitable valve means (not shown) wash water is admitted into tub 10, filling the same to a liquid level L which is maintained by a suitable control device (not shown) and which immerses more than one-half but less than all of the lint screen. During or before this filling operation the screen actuating solenoid 21 is de-

energized by operation of the aforementioned controls, so that spring 20 is free to force shaft 25 to the right, placing and holding screen 19 in the broken line position (FIGURE 3) wherein said screen is free to rotate. In this position drive wheel 26 engages lip 27 of the rotating drum 28. The lint screen is accordingly rotated and the wash water, which extends to the aforementioned approximate level L, is agitated thereby. Such rotation and agitation is desirably continued also during ensuing rinse operations, provided by the aforementioned control means.

Pursuant to drainage of water from tub 10, and when the control means initiates a high speed spinning operation of drum 28 for the extraction of water from the fabrics in this drum, rotation of screen 19 is no longer useful (in the absence of the washing and screen cleaning liquid) and no longer desirable (because of the high speed involved.) Solenoid 21 is therefore energized at this time, thereby returning lint screen 19 and drive wheel 26 to the full line position (FIGURE 3).

Shortly thereafter a drying operation is initiated by said controls, i.e. air blower and heater means (not shown) now maintain a circulation of hot air across the drum 28, which drum now again rotates slowly for the drying of fabrics therein. Said circulation of air continues as a current passing through the apertures of lint screen 19 and into drain chamber 15, thus providing for the filtering or screening of lint.

The air then passes through outlet port means 43, provided in wall 17 of the drain chamber, into air circulation chamber 16 and therefrom, desirably, into the suction of said air blower. The air can be recirculated or can ultimately reach the ambient atmosphere, or any suitable duct to the outside, through an aperture 44 in rear closure plate 11 (FIGURE 1). This air circulation and the attendant filtering of lint, at 19, are continued for a suitable period of time, chosen to dry the fabrics in drum 28 to a predetermined extent. Thereafter the operating cycle of the machine can be terminated with respect to the load of fabrics which has been mentioned and lint screen solenoid 21 can then be de-energized again.

Cleaning of the lint screen is achieved during the initial or washing phase of an ensuing cycle of operations, applied to a new load of fabrics, wherein wash water is again provided in tub 10 up to level L. The lint screen solenoid remains deenergized so that the screen and its drive wheel are again in the broken line position (FIGURE 3). Rotation of the screen with lint thereon and with agitation of the wash water has been found to provide unusually thorough removal of the lint. Such removal is aided by the splashing of water as portions of the lint screen emerge at water level L and are re-immersed therein. Additionally a pumping effect is provided by the conical shape of the immersed, rotating screen portion, which causes the water to flow through the screen apertures in the direction from the concave to the convex side of the screen disc, thereby contributing effectively to the clearing of the screen apertures.

The lint removed from the lint screen by these operations is mixed with the used wash water in tub 10 and is removed with that water, incident to the conventional draining of the machine at the end of the washing cycle and prior to the rinsing phase. For such drainage the tub 10 has a drain outlet sump 45 (FIGURE 2) this outlet being suitably drained and being connected also with a drain 46 of the air circulating chamber 16 and drain chamber 15.

This latter drain 46 is shown as having a U-shaped or V-shaped portion, or water trap, 47 incorporated therein. Pursuant to a draining operation which removes most or all of the water from chambers 10, 15, 16 and sump 45, a small amount of water is automatically retained in this trap. In this way simple but effective provision has been made for drainage of the drain and air circulating chambers 15, 16 on the one hand and of tub 10 on the

other hand and against bypassing of screen 19 during the air circulating operation. The water retained in trap 47 forces the circulating air to pass through the lint screen, where the lint is intercepted; the trap thus prevents short-circuiting of air through sump 45 and pipe 46 to the air circulating space 16.

Referring finally to the modified construction of FIGURE 4, an air circulation space 50 is again shown as confined between front and rear plates 51, 52 and a lint screen 53 again overlies a suitable aperture in the inner closure plate 52. Coaxially therewith an aperture is provided in the outer closure plate 51 which is closed by a flexible sheet 54. Drive wheel 55 and screen 53 are secured to shaft 57 which is slidably and rotatably supported in bearing structure 58. In this modified construction the flexible closure means 54 or a suitable portion thereof, is resilient; the resilience thereof is used to bias shaft 57, screen 53, and drive wheel 55 toward the left, that is into lint screening position, whereas a power means 59, here shown as a hydraulic actuator, is adapted to produce the axial movement of the unit into the broken line or right hand position for rotation and cleaning of the lint screen. Suitable valve means (not shown) are operated by the control means of the machine to cause 25 rightward motion of the free end of power means 59 as indicated by broken lines and thereby to initiate cleaning of the screen.

This modified embodiment is further shown as provided with linkage 60 connecting the lint screen shaft 57 with the shaft 61 of a suds door 62 in the aforementioned air circulation chamber 50, this door being associated with suitable partition structures so as to divide said chamber 50 into separate portions 63, 64 which are respectively located upstream and downstream of the suds door in the direction of the air circulation coming through and from the lint screen 53. Thus it will be seen that communication from 63 to 64 is open and substantially unobstructed when linkage 60 holds the suds 62 open while holding the lint screen 53 in stationary and screening position. At other times the linkage 60 closes chamber 50 to the air circulation by holding suds door 62 at or near the closing position thereof.

It is sufficient for this linkage to move the suds door to the vicinity of the seating surface for the same, as suggested by the broken line 62a; the air circulation then establishes appreciable back pressure across the suds door and tends to slam the same into fully closed position 62B. This final or slamming motion is allowed, while interference with the lint screen drive wheel engagement 55, 56 is prevented, by means of a small compression spring 65 suitably interposed between the suds door shaft 61 and the actuating portion of linkage 60.

While only two embodiments of the invention have been described, it should be understood that the details thereof are not to be construed as limitative of the invention, except insofar as is consistent with the scope of the following claims.

I claim:

1. In apparatus for washing fabrics in a tub and for drying the washed fabrics in said tub, said tub being arranged for removably maintaining a body of washing liquid therein for said washing:
means for circulating air into and from said tub to provide an air current for said drying;
a screen constructed and arranged during said drying to intercept and screen said air current, as the air current passes from said tub; and
means for moving said screen, during at least a portion of the time for said washing, in and through said liquid in order to clean the screen.
2. Apparatus as described in claim 1, also including a fabrics drum in said tub, for said washing, and means adapted to be driven by said drum to effect said rotating of the screen.

3. In a combination fabrics cleaning and drying machine:
- a tub;
  - means for selectively providing presence and absence of fabrics cleaning liquid, and of a fabrics drying air current, in said tub;
  - a plate having perforations therein, normally overlying an aperture in an upstanding wall of said tub, said plate being adapted partly to be submerged in said fabrics cleaning liquid in said tub;
  - drive means for rotating said plate in and through said liquid in the tub; and
  - means for reversibly shifting said plate into peripheral engagement with edge portions of said wall, sur-

rounding said aperture, in such a way that said drive means can no longer effect said rotating of the plate and that the perforated plate then filters said air current.

- 5 4. Apparatus as described in claim 3 wherein said plate is substantially conical in order to force fluid through the perforations of the plate when the plate is rotated.
